UNITED STATES PATENT OFFICE.

LOUIS L. KAESZ, OF RICHMOND HILL, NEW YORK.

MODEL-AIRPLANE.

1,333,257.

Specification of Letters Patent. Patented Mar. 9, 1920.

Application filed March 21, 1919. Serial No. 284,000.

To all whom it may concern:

Be it known that I, LOUIS L. KAESZ, a citizen of the United States, residing at Richmond Hill, in the borough of Queens 5 and State of New York, have invented a new and useful Improvement in Model-Airplanes, of which the following is a specification.

This invention relates to model airplanes, 10 and my improvements are directed toward means for simplifying their construction, as also for rendering them strong, easily assembled and disassembled, and capable of adjustment for longitudinal and lateral 15 balance.

Flying models contribute an important phase to the art of aeronautics, because they are handled by young people who may thereby acquire their inception in aviation and 20 learn something about the sustentation of heavier-than-air machines; and it is my purpose to render available model airplanes which are more or less aerodynamically correct, to possess a measure of educational 25 value, that their handling may prove instructive as well as entertaining.

Therefore my invention comprises the use 30 of wings built up of ribs and beams, with a suitable covering to provide pressure and upper surfaces having aerofoil contours; and means for securing said wings to the airplane frame in adjustable manner, both as regards their longitudinal and lateral 35 relation.

Also, the frame structure, which consists 40 of longerons that converge toward one end, has novel means for the detachable engagement of two propellers at its other end; and novel combined means for securing the vertical stabilizer and for providing engaging 45 means whereby the elastic power bands, which extend from the propellers, may be suitably held.

Still further my invention includes the 50 employment of a winding device operable by two meshed pinions, which are revolute oppositely through a hand-driven gear in mesh with one of said pinions, and the shafts of said pinions engaging adjacent ends, respectively, of said power bands, whereby the latter may be wound to generate propulsive force in the propellers.

Other features and advantages of my said invention will hereinafter appear.

In the drawings:—

Figure 1 is a plan view of my improved 55 model airplane.

Fig. 2 is a section on the line 2—2 of Fig. 1.

Fig. 3 is a detail of the duplex winding 60 means for the power bands.

Fig. 4 is a partial plan view of the frame, and

Fig. 5 is a side elevation of Fig. 4.

In the example of my invention illustrated in Fig. 1, let 1—1 indicate the frame longerons, which are converged forwardly, and at their rearward, separated ends are connected by a transverse member 2; an intermediate reinforce strut 3 also being provided.

Adjustably and removably mounted upon the frame are the wings 4 and 5, which, respectively, comprise the main supporting surface and the tail surface. Said wings 75 are similarly constructed, and, as shown in Fig. 2, have the ribs 6, with beams 7 extending transversely therethrough, a strip of cane 8 which extends all around the wing edge, and a suitable covering 9.

Each wing is secured to the longerons by elastic bands, as 10, which, engaging each at two points beneath a longeron, and being drawn up thereover, thus form a loop to receive the wing, and to tensionally bind upon 85 the upper surface thereof. It will be seen that through this simple means of connection between the wings and the frame, the positions of the wings, both longitudinally, and with regard to their lateral balance, are 90 adjustable with the greatest convenience. Also, as is evident, the wings are easily demounted by the mere removal of the elastic bands.

Brackets, as 11, are secured to the expanded ends of the longerons, holes in said brackets serving as bearings for the propeller shafts 12. These shafts are each composed of a piece of wire that is secured to the propeller and formed into a hook 13 100 adapted to engage the elastic bands 14, which, at their opposite ends similarly engage hooks 15, that are secured to the converged ends of the frame longerons. As shown in Fig. 1 the hooks 15 are engaged 105 by eyelets 16 that extend from a cap piece 17 fitting over the converged terminal ends of the longerons, and bound by lashing 18,

The vertical stabilizer 19 is fitted between the longerons at this point and is thus also secured by the lashing. According to usual practice the elastic bands are removed from 5 the hooks 15 to twist them.

Certain other features are shown in Figs. 3, 4 and 5. Thus, in Fig. 3, will be seen a novel means for twisting oppositely the elastic bands to store energy for rotating the 10 propellers. The band hooks 15 are here shown as disengaged from the eyelets 16, and caught in eyelets 20 which extend from the shafts of intermeshing pinions 21, 22: one of said pinions meshing with a crown gear 23, pivoted to a bracket or support 24, that also carries said pinions. The bracket 24 is provided with a handle 25, and the gear 23 also has a handle 26 by which it may be rotated, to thus revolve pinions 21, 22 and 15 20 twist the elastic bands. When twisted to a suitable tension the bands 14 are removed from eyelets 20 and returned to eyelets 16 to then impart rotation to the propellers.

The support for hooks 15 may be in the 25 form of a triangular plate 27, which fits within a slot 28 in the converged ends of the longerons (see Fig. 4), and is secured therein as by lashing, said plate having at its lateral corners the holes 29 to receive 30 said hooks; and the vertical stabilizer 30, which fits between said longerons, also having a slot to receive said plate.

Fittings for the transverse frame members, as 31, may consist of a piece of sheet metal

32, placed against the inner surface of a 35 longeron, and secured thereto as by pins 33; said piece 32 having lugs 34 which embrace the abutting end of a strut and are secured thereto as by pins 35.

Variations may be resorted to within the 40 spirit and scope of my said invention and parts thereof used without others.

I claim:

1. In a frame for model airplanes, in combination, converged longerons having a horizontal slot at their converged ends, and a plate fitted in said slot, said plate having laterally extended portions at opposite sides of the frame with means for engaging the propeller driving bands. 45

2. In a frame for model airplanes, in combination, converged longerons having a horizontal slot at their converged ends, a vertical stabilizer fitted between said longerons and having a slot aligned with the slot in said 55 longerons, and a plate fitted in said slots to unite said members, said plate having laterally extended portions at opposite sides of the frame with means for engaging the propeller driving bands. 50

In testimony whereof, I have signed my name to this specification in the presence of two subscribing witnesses, this 10th day of February, 1919.

LOUIS L. KAESS.
